DESIGN FOR A LIGHTING FIXTURE

Thomas A. Carter, Jr., Grand Rapids, Mich., assignor to Grand Rapids Store Equipment Company, Grand Rapids, Mich., a corporation of Michigan

Application December 11, 1939, Serial No. 88,818

Term of patent 7 years

To all whom it may concern:

Be it known that I, Thomas A. Carter, Jr., a citizen of the United States, residing at the city of Grand Rapids, in the county of Kent and State of Michigan, have invented a new, original, and ornamental Design for a Lighting Fixture, of which the following is a specification, reference being had to the accompanying drawing, forming a part thereof.

Fig. 1 is a perspective view of a lighting fix-ture showing my new design, viewed from the under side.

Fig. 2 is a fragmentary cross section of the lighting fixture illustrating the contour of the lower surfaces.

I claim:

The ornamental design for a lighting fixture, as shown.
